UNITED STATES PATENT OFFICE.

JOHN GLENNIE HOLBOURNS AND WILLIAM MORRIS BOWER, OF LONDON, ENGLAND,
ASSIGNORS TO LINOTYPE AND MACHINERY LIMITED, OF LONDON, ENGLAND, A
BRITISH COMPANY.

MECHANICALLY-CAST TYPE BAR AND MEANS FOR PRODUCING SAME.

Application filed September 1, 1927, Serial No. 216,838, and in Great Britain September 30, 1928.

In the use of mechanically cast type-bars or slugs for the production of long-measure work, particularly in connection with type of the larger body dimensions, it is usual for the 5 matter constituting each line to be cast on a plurality of slugs which are butted, that is to say, assembled end to end, in the form or chase. With such butted slugs there is a tendency for their adjacent ends to become 10 relatively displaced, so that considerable care has to be exercised in locking up the slugs in the form in order to ensure accurate registration of the portions of each printed line represented by the respective slugs.

15 The present invention has for its object to produce slugs so formed that the above-mentioned displacement will be prevented, and the work of making up the forms thereby facilitated.

20 According to the invention, the abutting ends of adjacent slugs are provided with interlocking or mutually engaging surfaces serving to maintain the lateral alignment of the slugs when butted in the form.

25 In a preferred constructional form of the invention, each slug is provided at one end with a groove or recess extending in the direction of the height to paper, and at the opposite end with a correspondingly positioned tongue or projection. Consequently, the abutting ends of successively cast slugs will interlock by their tongues and grooves in such a manner as to prevent any displacement of said ends transversely of the line.

30 The before-mentioned tongues and grooves may be conveniently produced when casting a slug in the usual form of mould employed in typographical casting machines such as those known commercially under the trade mark 35 "Linotype" by providing an appropriate groove and tongue in the respective end liners constituting opposite end walls of the mould slot. When the slugs are so cast, a complete line embodying a plurality of such slugs will, 40 of course, present a projection at one end and a groove at the opposite end, but such projections and grooves will not disadvantageously affect the locking up of a series of lines in the form. If desired, however, for the production 45 of lines each comprising two slugs, two moulds may be employed in alternation, one end liner of one of the moulds being grooved

and the opposite end liner of the other mould being tongued.

The invention will now be described by reference to the accompanying drawings in which:—

Figure 1 is a perspective view of two of the improved slugs as seen from their inner or mutually interlocking ends; 60

Figure 2 is a similar view of the same slugs inverted and as seen from their outer ends;

Figure 3 is a perspective view of the interlocked parts of two complementary slugs;

Figure 4 is an elevation of a mould for casting the slugs shown in Figures 1, 2 and 3, and 65

Figures 5 and 6 are detached perspective views of the liners by which the grooves and tongues respectively are cast.

Slugs to be interlocked according to this 70 invention, are formed, one say A, with a groove or recess 1 extending in the direction of the height to paper, and the other, say B, with a correspondingly directed tongue or projection 2 adapted to fit into the said groove 75 which latter, as shown in Figure 3, is preferably of greater depth than is the tongue.

As a result of this construction, when the 80 two ends of the slugs A, B, are juxtaposed they are interlocked by the mutual engagement of the tongue and groove in such a manner as to prevent any displacement of said ends transversely of the printing line.

It will be noted that the grooves and 85 tongues extend from the feet of the slugs up to what is known as the shoulder 3, that is, well below the printing face 4, so that when the slugs are locked in a form or chase they can shift neither transversely of the line nor in the direction of height to paper. It will 90 also be noted that the recesses usually provided for preventing rearward movement of the slugs in the casting mould are here correspondingly provided and, as shown in the drawings, where they are identified by the 95 numeral 5, are, in each case, divided by the tongue 2 or formed in the bottom of the groove 1.

The before mentioned tongues and grooves 100 may be conveniently produced when casting a slug in the usual form of mould such as is shown in Figure 4, for which purpose the end liners 6, 7, (Figures 5 and 6) are provided, on their casting faces, the former with

a rib 8 for forming the grooves 1 and the latter with a groove 9 for forming the tongues 2. Slugs cast in a mould such as represented, each present a groove 1 and a tongue 2 at respectively opposite ends, but such grooves and tongues do not disadvantageously affect the locking up in the form of a series of lines of such slugs. If desired, however, for the production of lines each comprising only two aligned slugs, two moulds may be employed in alternation, one mould with an end liner 6 having a rib 8 for forming the grooves 1 and its second end liner of ordinary un-grooved construction, and the other mould 15 with an end liner as 7 having a groove 9 for forming the tongues 2 and its second end liner of ordinary unribbed or plane formation; with such an arrangement complementary slugs will be produced with tongues and 20 grooves provided at only their meeting ends.

Having described our invention, we declare that what we claim and desire to secure by Letters Patent is:—

1. In or for a printing form, two complementary type-bars or slugs arranged end to end in abutting relation, said slugs at their abutting ends being formed with mutually engaging surfaces which maintain the lateral alignment of the slugs.
2. In or for a printing form, two complementary type-bars or slugs arranged end to end in abutting relation, said slugs at their abutting ends being formed one with a groove and the other with a tongue fitted thereinto, 35 said tongue and groove extending in the direction of height to paper and acting to maintain the lateral alignment of the slugs.
3. A type-bar or slug having a printing face and formed at one end within the ef-

fective length of its printing face with a 40 groove extending in the direction of height to paper.

4. A type-bar or slug having a printing face and formed at one end within the effective length of its printing face with a 45 tongue extending in the direction of height to paper.

5. A type-bar or slug formed at one end with a tongue extending in the direction of 50 height to paper and at its opposite end with a similarly extending groove of the same cross sectional contour as that of said tongue.

6. The method of preparing a printing form composed of complementary type-bars or slugs arranged end to end in abutting relation, which consists in producing the complementary slugs at their abutting ends with 55 mutually engaging surfaces to lock said slugs against relative lateral displacement.

7. The method of preparing a printing form composed of complementary type-bars or slugs arranged end to end in abutting relation, which consists in producing the complementary slugs at their abutting ends one 65 with a groove extending in the direction of height to paper and the other with a similarly extending tongue to fit said groove whereby to lock said slugs against relative lateral displacement.

8. A method as in claim 6, characterized by 70 the fact that the complementary slugs are cast in molds having their end walls fashioned to produce the mutually engaging surfaces.

In testimony whereof we have affixed our signatures hereto.

JOHN GLENNIE HOLBOURN.

WILLIAM MORRIS BOWER.
